Des. 183,530

Patented Sept. 16, 1958

183,530

COMBINED KNIFE SHARPENER HOUSING AND HANDLE

Thomas Lamb, New Canaan, Conn.

Application May 13, 1957, Serial No. 46,142

Term of patent 14 years

(Cl. D37—1)

I claim:

The ornamental design for a combined knife sharpener housing and handle, substantially as shown.
